United States Patent Office

Des. 217,573
Patented May 12, 1970

217,573

SAFETY PAPER OR SIMILAR ARTICLE

Carl Couve, Rolling Meadows, Ill., assignor, by mesne assignments, to The Mead Corporation, Dayton, Ohio, a corporation of Ohio

Filed Mar. 21, 1969, Ser. No. 16,362

Term of patent 14 years

Int. Cl. D19—05

U.S. Cl. D59—6

FIG. 1

FIG. 2

FIG. 1 is a plan view of a safety paper showing my new design; and

FIG. 2 is an enlarged fragmentary view thereof.

I claim:

The ornamental design for a safety paper or similar article, as shown.
